UNITED STATES PATENT OFFICE.

JOHN GEARON, OF BELOIT, IOWA.

SCYTHE-SNATH.

SPECIFICATION forming part of Letters Patent No. 235,425, dated December 14, 1880.

Application filed June 16, 1880. (No model.)

To all whom it may concern:

Be it known that I, JOHN GEARON, of Beloit, in the county of Lyon and State of Iowa, have invented a new and useful Improvement 5 in Scythe-Snaths, of which the following is a specification.

Figure 1 is a plan view of the improvement. Fig. 2 is a rear elevation. Figs. 3 and 4 show a modification of the left-hand handle.

10 The object of this invention is to furnish scythe-snaths so constructed that they may be readily adjusted as the different persons who are to use them may require.

The invention consists of a scythe-snath 15 formed of three parts halved to each other, secured by bolts and provided with projections, corresponding depressions, and handles, as hereinafter described.

20 Similar letters of reference indicate corresponding parts.

A represents the scythe, in the heel of which is formed a hole to receive the bolt B, by which it is secured to the lower end of the lower part, C, of the snath. Upon the upper side 25 of the heel of the scythe A are formed projections D, which fit into corresponding depressions E in the part C of the snath, so that the scythe A will be held securely in place by tightening the nut of the bolt B. The projections and depressions D E are so formed that 30 the point of the scythe A may be set in or out, as the mower may desire. The upper end of the part C and the lower end of the part F of the snath are halved to each other, and are 35 secured together by the bolt G, that carries the right-hand handle H, the joint being so formed that the parts C F of the snath may have a vertical adjustment, so that the edge 40 of the scythe A can be set up or down, as circumstances may require. The adjacent faces of the joint between the parts C F are pro-

vided, the one with projections I, and the other with depressions J, so that the said parts C F will be held securely in place when adjusted. The upper end of the part F and the lower 45 end of the part K are halved to each other, and are secured together by a bolt, L, so that the said part K can be adjusted forward or back, as may be desired. The adjacent faces of the parts F K are provided, the one with 50 projections M, and the other with corresponding depressions N, so that they will be held securely in place when adjusted.

To the outer end of the part K is secured the left-hand handle O by a screw, P, screwed 55 into the end of the said part K. If desired, the left-hand handle O may be placed between the arms of a U-shaped bar, Q, which has a screw, R, formed upon its bend to be screwed into the end of the part K of the snath, as 60 shown in Figs. 3 and 4. In this case a noteh, S, may be formed in the end of one of the arms of the bar Q, to adapt the said bar to be used as a wrench to loosen the nuts of the various bolts, so that the snath can be adjusted 65 at any time.

With this construction the scythe and snath can be adjusted as the character of the mowing and the wishes of the mower may require.

Having thus fully described my invention, I 70 claim as new and desire to secure by Letters Patent—

A scythe-snath constructed substantially as herein shown and described, consisting of the three parts C F K, halved to each other, secured by bolts G L, and provided with projections I M and corresponding depressions J N, and the handles H O, as set forth.

JOHN GEARON.
